OIL BURNER

René M. Vidalie, San Francisco, Calif., assignor
to Ray Burner Company, San Francisco, Calif.,
a corporation of Delaware

Application March 11, 1931, Serial No. 521,855

13 Claims. (Cl. 158—28)

This invention relates to an oil burner, and particularly to a unit construction for the same whereby a simple, compact, and relatively inexpensive oil burner is provided for domestic or 5 industrial installation, the construction being such that the burner will require, relatively, a minimum of attention. This application is a continuation in part of my copending application, Serial No. 436,086, filed March 15, 1930.

10 The invention is also concerned with the provision of a burner construction of such a nature that the starting up operation of the burner is facilitated. In this connection, I prefer that a resistance element be utilized in combination 15 with a suitable refractory support block, the two being so positioned that the resistance element can heat the support block but does not contact with any liquid oil. The block is positioned to receive liquid oil from the oil atomizing means 20 of the burner. This oil vaporizes on the heated block and the vapor thus generated becomes ignited upon contact with the hot resistance element to start the burner.

25 Previous oil ignition devices for burners of the type herein considered have, in some instances, employed a high tension current. These, therefore, required a relatively expensive transformer installation and the provision of a high grade of insulating material, necessarily expensive.

30 The resistance element, which I preferably employ, is adapted to be connected directly to a power line, as a 110 volt line, furnishing either alternating or direct current. This makes the burner, as shipped from the factory, capable of 35 installation directly, irrespective of whether the supply is direct or alternating current. This is quite an advantage since it is less expensive and since high tension ignition cannot be effected cheaply from direct current lines.

40 In accordance with my invention, I provide the ignition means in such a manner that the electrical resistance element, after ignition of the oil has taken place and the resistance unit is cut out of service, is protected from the heat 45 of the burning oil and from radiant heat from the fire box. This prolongs the life of the element materially.

The present invention also contemplates regulation of the air supply to the burner used for 50 effecting a secondary atomization of the oil, as will presently appear. The regulation is in such a manner that ignition of the oil is facilitated, being controlled so that a positive ignition is assured in every instance. I have observed that 55 previous control of the air to effect a secondary

atomization in oil burners has been such that the initial ignition of the oil was frequently rendered ineffective, the flame actually being blown out upon application of the secondary air.

5 My invention also contemplates the regulation of the voltage applied to the resistance element so that a practically constant temperature of the element is assured, thus prolonging the life of the element. In actual installations I have observed that where 110 volt line voltage is ordinarily spoken of, the actual line voltage, upon measurement, varies between 85 and 145 volts. A voltage as low as 85 volts is not sufficient to raise the element to a high enough temperature to result in, and enable, positive oil ignition; 145 10 volts is so high that a deleterious effect is had upon the resistance element, due to overheating. I therefore include a suitable regulating means such as a ballast resistor in the circuit with the electrical resistance so that the voltage passed 15 through the electrical resistance element is so regulated that the temperature of the resistance element is kept relatively constant and is not subject to the 1100° F. or 1200° F. difference in 20 temperature which can be occasioned by an increase of the line voltage from 85 to 145 volts, which occurs if no regulation is employed.

25 The invention possesses other advantageous features and objects, some of which, with the foregoing, will be set forth at length in the following wherein I have outlined a preferred form of 30 the oil burner of my invention. In the drawings, which form a part of the present specification, I have illustrated a burner embodying the aforementioned preferred form of the invention. 35 However, it is to be understood that this form is only the preferred form and that modifications can be made without departing from spirit and scope of my invention. The appended claims are to be accorded a range of equivalents consistent 40 with the state of the prior art.

45 In the drawings, Figure 1 is a side elevation partly in section of a burner of my invention.

Figure 2 is an enlarged view of the oil discharge pipe.

Figure 3 is a section taken along the line 3—3 of Figure 1 illustrating the coupling construction.

Figure 4 is a section taken along the lines 4—4 of Figure 1, illustrating the shutter control mechanism.

Figure 5 is a section taken along the line 5—5 of Figure 4 illustrating further details of the shutter control mechanism and the rear end of the burner.

55 Figure 6 is a front elevation of the refractory

insulating block support and resistance element utilized for effecting ignition of the oil.

Figure 7 is a rear view of the block and resistance element shown in Figure 6.

5 Figure 8 is a section taken on the line of 8-8 of Figure 6 illustrating a section through the block and the manner of providing a terminal and a connection to the resistance element.

10 Figure 9 is a section taken along the line 9-9 of Figure 6, illustrating the construction of the resistance block.

Figure 10 is a section through a form of means for supplying an excess of oil to the atomizing cup and the electrical ignition means.

15 Figure 11 is another form of device useful in supplying excess oil to the atomizing cup and the electrical ignition means.

20 Figures 12 to 14 inclusive are diagrammatic showings of various oil burner ignition installations contemplated by my invention.

Figure 15 is a section taken through the ignition block, element, oil atomizing means, and oil supply pipe, showing certain other features of my invention.

25 Figure 16 is a section taken along the line 16-16 of Figure 15.

The preferred form of the oil burner herein depicted is that type which includes a cup upon which oil is discharged as the cup is revolved rapidly to atomize the oil upon its being thrown off the cup by centrifugal force. The burner shown includes a suitably formed metal cup 21 positioned upon a rotatably mounted shaft 22 which is adapted to be driven at a relatively high rate of speed. Oil, supplied from a supply line 23 through an orifice 24 therein, as is shown in Figure 2, is discharged upon the rapidly spinning cup to be subsequently whirled off and atomized by the centrifugal force imparted to the oil.

40 While certain features of my invention are particularly concerned with this particular means of effecting atomization, there are other features of the invention that can be employed with other oil atomizing means. The rotary cup is here depicted as the preferred form of atomizing means but, as may be inferred from the above, other types of atomizing means for the oil may be employed within the skill of those versed in the art.

45 The present invention is, from one aspect, particularly concerned with the ignition of the oil whirled off the atomizing cup over lip 26 thereof. The ignition means, in the present instance, preferably includes a suitable supporting means such as a block 27 of a suitable material having the necessary high electrical resistance, refractory properties, and being resistant to attack from the oil sulphur content.

50 This block, as is best shown in Figures 1, 6, 7, 8, 9 and 15, is adapted to be cooperatively positioned with respect to the atomizing cup and particularly the lip 26 thereof. In its preferred form, the block is generally circular in outer contour and has a central passage 28 through which the atomizing cup partially extends. This central opening is formed by the angularly provided faces 29 and 31 which extend away from each other toward opposite faces of the block. A channel 32 is formed in the block and preferably 55 extends almost entirely around the outer periphery of the block. Within this channel an electrical resistance element 33 is positioned. This element is formed of a suitable resistance material, preferably an alloy of nickel and chromium of either one of the following compositions:

I	
Nickel	80%
Chromium	20%
II	
Carbon	.15%
Mang.	.50-.70
P & S	.035 max.
Silicon	.70-.1.50
Nickel	19.00-21.00
Chromium	25.00-26.00
Iron	balance

It is to be noted, as is best shown in Figures 6, 7, 8, 9 and 15 that the wire is well down in the channel and that the relation between the wire and the face 31 is such that direct contact of oil with the wire is practically impossible while vaporized oil can contact with the hot element for ignition. Accordingly, the face 31 is so fashioned that the plurality of shoulders 34 and depressions 35 are formed therein as appear in Figures 6, 8 and 9 so that liquid oil can pass relatively close to the heating element without actually contacting therewith. Further, the element is disposed on the block so that free vapor and air circulation can take place over it. Oil, contacting with the refractory block, heated by means of the resistance element upon electrical power being passed therethrough, becomes vaporized and, upon contact of the vapor with the heating element, ignited.

It is my observation that the direct contact of the oil with the hot element does not serve to ignite the oil and, over a period of time, this contact is not beneficial to the heating element, appearing to have an actual deteriorating effect upon the composition of the element. It is therefore to be noted that the element is so positioned, with respect to the atomizing cup, and with respect to the block, that it is out of the normal path of oil discharged from the cup and substantially out of contact with oil striking the supporting block.

The shoulders 34 are continued beyond the face 31 and include projections 36 which are slightly hooked over, as shown in Figures 6 to 9 inclusive, to hold the wire in position in the channel, although the channel is wide enough so that the wire can be readily removed and inserted by manually manipulating it over the projections and in the channel.

The heating element 33 is connected at each end to connectors 41 which extend through the block and engage the ends of the element. It is to be particularly noted, as shown in Figure 8, 55 that the connectors each include a shoulder 42 which engages the bottom of depression 43 provided in the outer face of the block. An end 44 of each of these connectors extends for a considerable distance from the block, the end being 60 enclosed in a sheath 46 formed on the block. I have found this construction advantageous inasmuch as possible electric breaking down of the block from contact with oil is obviated, inasmuch as a very long path of refractory material has to break down before a short circuit can actually take place across the connectors.

To prevent the heat of the burning oil and radiant heat from the fire box from affecting deleteriously the resistance element, and to ensure a long life to the element in operation, means are preferably provided for preserving the element substantially at atmospheric temperature at all times during operation of the burner, even though the element is exposed to the direct heat 75

and radiant heat from the burning oil in the fire box into which the burner is discharging. These means preferably include a passage 48, which extends through the block so that air can be circulated over and about the element. The passage 48 is, for structural reasons in manufacture of the block, preferably made up in a plurality of segments.

To enable an adequate air circulation over the element adjacent to the point where the projections 36 extend over the passage, a plurality of cuts 49 are formed in the block adjacent to the projections, as is best shown in Figure 7, so that air circulates adjacent the underside of the element and against the projections. The shoulders 51 formed by provision of the cuts, enable the element to be adequately supported and retained in position upon the block.

Means are also provided for draining oil, dripping from the atomizing cup, into the fire box of the furnace. In the block shown in Figures 1, 6 and 7, this includes a channel, or slot, 52 formed on the lower portion of face 31 of the block so that dripping oil will be directed into the fire box.

In Figure 15 I have shown another block and drain construction which possesses the advantage of obviating almost entirely, the undesirable contact of the oil drip with the block. This includes a drain pipe 53 extending from air discharge nozzle 63 through a slot 54 in the block to the fire box. A vane member 55 is cast across the lower side of the nozzle 63, as appears in Figure 16, in back of the connection to the drain pipe, so that dripping oil collecting in the nozzle is passed into the drain. What little oil does drain off the lip 26 of the atomizing cup is of such a small quantity that the block is not materially affected thereby.

The block and its electrical resistance element are preferably held in cooperative relation to the atomizing means by a nipple 56 to which the block is fixed by means of a set screw 57 engaging a notch 58 in the block. The block is positioned with the slot 52 at the lowermost point. The nipple is conveniently carried upon the oil burner structure and, as is best shown in Figure 1, is preferably mounted and secured upon a ring 59 extending from casing 61.

The nipple 56 includes one or more apertures 62 for admitting air between the nipple and the air discharge nozzle 63 which is cooperatively extended about the rotating cup 21. These apertures serve to admit atmospheric air so that the air passes through the passages 48 in the block and cools the resistance element as previously set forth. When the oil burner is in operation, particularly in connection with a very hot fire box, circulation of air is naturally induced through the apertures 62 and through the passages 48 so that the element is kept cool. Atmospheric air at atmospheric temperature is therefore supplied to the element and keeps the element at practically the temperature of the atmosphere at all times except when the element is energized by electrical power. In some instances, instead of depending upon the natural air circulation, it may be desirable to utilize a portion of the secondary air supply, or air utilized for effecting secondary atomization, as by providing a hole in the casing 61 so that air is passed to the heating element and is thereby kept cool when not energized.

In the present form of burner, an air supply under pressure is preferably furnished by a fan 66. This fan includes a runner comprising a plurality of blades 67 carried upon a suitable hub

structure 68 which is in turn mounted upon the shaft 22 for rotation therewith within the housing formed by the casing 61 and casing 78. Vanes 69 are provided upon the casing 61 for directing the air into the discharge nozzle 63. Air from the nozzle is directed by vanes 64 about the rotating atomizing cup and the lip 26 thereof. This air effects, what I have previously termed, a secondary atomization of the oil discharged off the cup lip. It is not the only air supply usually, 10 other air being generally admitted past the nipple 56.

The air supply for the fan is preferably drawn through a supporting housing structure 71 which includes bearings 72 for rotatably mounting the 15 shaft 22. These bearings are preferably of the plain babbitt type although roller bearings may be utilized. I have found that the plain bearings are practically noiseless and therefore utilize them where this factor is material. The housing and supporting structure 71 is formed with an air passage way 73 therein so that air passes through the housing from the end 74 thereof to the fan. The air, drawn from the atmosphere, is circulated over the bearings and keeps them 25 cool even though they are relatively close to the burner.

Means are provided for furnishing lubrication to the bearings 72. These means include conduits 78 through which a lubricant can be injected into a chamber 79 surrounding the bearings. This chamber includes an opening 81 which is normally closed by a plate 82. A suitable fibrous material 83 as wool can be placed in the chamber and, when saturated with a lubricant, serves to supply the lubricant to the bearings 72 through slots 84 provided through the bearings, the wool contacting directly with the rotating shaft. The portion of the shaft which extends between the bearings 72 is enclosed by 30 a suitable member 86 carried upon the bearings. 35

As has been previously set forth, the oil is supplied to the rotating atomizing cup through an aperture 24 provided in the upper side of the shaft or oil pipe 23. This pipe, as is best shown 45 in Figure 2, includes several circular cuts 87 adjacent to the aperture and extending completely about the oil supply pipe. These prevent the oil from creeping back along the outside of the oil supply pipe. 50

Another form of oil discharge means from the pipe 23 is shown in Figure 15. This means comprises a plug 251 inserted into the pipe and having an angularly formed shoulder 252 which abuts the end of the pipe. The plug extends from the 55 pipe to an end portion 253 which comprises angular shoulders 254 extending from a common constricted base at an angle of about 45°. An outlet hole 256 is drilled in the end through the constricted base and into duct 257 which extends 60 to the oil pipe. The plug is placed in the pipe with the hole 256 facing upwardly. In practice, I have found this construction advantageously employed to prevent oil leakage of the pipe when the burner is not operating. The burner can be 65 tipped forward at quite an angle before the oil will drain out.

The oil supply pipe 23 extends through the hollow shaft 22 from a hollow bracket member 88 in which it is centrally positioned by a plurality of 70 set screws 89 carried in the bracket member. These set screws enable the oil supply pipe to be adjusted relative to the hollow shaft 22 so that it clears and does not rub against the shaft during rotation. The hollow bracket member in 75

cludes a drain 90 through which oil traveling back along the outside of pipe 23 can pass.

The oil pipe is carried in and is secured to a member 91 which is fixed to the bracket 88. This member, as is shown in Figures 1 and 5, is adapted to be connected to a source of oil supply, which can include the pump, control devices, and reservoir carried in casing 92, through an adjustable oil metering device such as an adjustable aperture indicated at 94 in Figure 1 or metering device 93 shown in Figure 15.

The metering device shown in Figure 15 is particularly capable of enabling the burner to start the first time, even though the burner has been idle for some time. Present day fuel oils are not absolutely free of sediment, asphalt bodies or free carbon, so that, when regulation of the oil to the burner depends upon the use of a restricted orifice, clogging of the orifice frequently occurs. In the form of device shown, the member 91 includes a passageway 95 which extends angularly with respect to and extends beyond the level of the oil inlet connection 96 and the duct 97 which passes to the pipe 23. A threaded plug 98 having a passage 99 therein. A thin apertured metering disc 100 of a metal as monel metal is soldered onto the end of the plug and forms a closure for the passage 99. It is to be noted that the disc is above the oil level in the duct 97 so that when the burner is not operating, the apertured disc is out of the oil. This leaves the aperture free, while sediment can settle into the bottom of the passageway 95 and away from the disc. When the burner starts up and oil is passed through the metering disc, the aperture therein is free. The plug 98 can be withdrawn and replaced with another plug carrying another size of metering disc so that the quantity of oil supplied to the atomizing means can be varied and controlled.

Means are provided for regulating the air admittance into the housing 71 and the fan 66. These means, in the preferred form of the invention, include a fixed shutter member 101 secured to the housing and a movable shutter member 102. A sheet metal shield 103 is extended about the shaft 22, where it projects from the rear bearing 72, to seal the shutters adjacent to the shaft. This shield 103 includes a shoulder portion 104 supporting a spring 106 positioned between the shoulder and the adjacent shutter member 102 so that the two shutter members are forced together by the tension of the spring.

Means are also provided for controlling the shutters. The operation of the shutter control mechanism is automatic and in accordance with the desired operation of the burner, as will presently appear.

At this time I wish to clearly point out and indicate that there are three possible modes of operation of the ignition means provided for the oil atomizing means.

The first mode of operation is that which results in the shutting off of the air, as from or to the fan, so that secondary atomization of the oil does not take place. The effect of shutting off the air supply to the atomizing means is that the secondary atomization, and deflection of the oil as it is discharged off the rapidly whirling cup, does not take place, and the oil does not traverse its normal path. Instead, the oil spreads out fanwise, striking upon the hot refractory block and becoming ignited.

The second mode of operation is that wherein the air supply is not interrupted while an excess of oil is supplied initially to the burner as it

starts. The excess is such that complete and effective atomization of the oil is impossible due to the extraordinarily large volume of oil. Some of the oil, therefore, finds its way to the hot refractory block and becomes ignited, with the result that adjacent atomized oil also ignites and the burner starts into operation.

The third manner of operation is that in which operation is achieved by shutting down the air supply, at least in part, while supplying an additional quantity of oil initially to the atomizing means with the result that unatomized oil spatters upon the hot refractory block and becomes ignited, whereupon the burner starts in operation.

The first manner of operation, that of shutting off the air supply, is secured by use of the shutters 102 and 101, previously described. These shutters are preferably controlled so that when the burner is not operating they are shut to cut off the air supply. Subsequently, upon the burner being started up, and as oil is supplied to the atomizing cup, secondary atomization does not take place because the air is not available and the oil is sprayed upon the previously heated refractory block.

The operation of opening and closing the shutters is preferably responsive to the supplying of oil supplied to the atomizing cup. The means for effecting the shutter control include a pressure responsive device 111 positioned in chamber 112 in the casing 92 so that upon creation of pressure in the chamber by the pump mechanism 113, piston 114 moves rod 116 which is secured to it. The contractile and expandable device 111 is conveniently formed by a metallic bellows 117 which is conveniently fixed by being secured to a supporting plate member 118 which is positioned upon the casing 92.

The bellows is enclosed in a cylinder 119 into which oil can enter through aperture 121. The rod member is joined to the piston 114 and extends therefrom through an aperture 123 to a bell crank 127. This construction provides an expandable and contractile cell and seals the oil within the pump casing.

The rod 116 is hinged as at 126 to bell crank 127 which is supported on the casing 92. The bell crank includes an adjustable stop 128 to control its throw. The bell crank is mounted upon a rotatable shaft 129 which includes a crank arm 131. A rod 132 is joined to the crank arm 131 by means of a swivel 133 from which it extends to the shutter member 102 and to which it is adjustably joined by means of swivel 134 movably secured in a slot 136.

The shaft 129 also carries adjustably a counterweight 141 which is so positioned as to bias the piston 114 and rod 116 to extended position. I prefer that a counterweight be employed for this purpose rather than a spring since the counterweight is positive in action, is not affected by temperature and is sure and positive in operation, although a spring can be employed, being placed inside the bellows.

The casing 92 includes a suction compartment 142 into which oil is drawn through fitting 143 from an oil supply by a pump mechanism 113. The pump mechanism 113 preferably includes two gear pumps 144 and 145 mounted upon and driven by a common drive shaft 161. An intermediate chamber 146 is provided in the pump casing into which oil is discharged by one pump and from which it is picked up by the second pump through suction pipe 152 to be delivered into pressure reservoir chamber 153. From this chamber, oil is

finally delivered to the burner through an outlet control flow device indicated generally at 154. This control device is responsive to the pressure built up in the chamber and will not release oil until the proper pressure is raised. When the pressure falls below this limit the device operates to shut off the flow. An excess pressure device 158 is also included which is adapted to by-pass excess oil delivered to the reservoir chamber.

10 The pumps 144 and 145 are preferably provided upon a common shaft 161 and which is suitably sealed into the pump housing by an oil seal bearing 162. The shaft 161 includes a coupling member 166 which, as is shown in Figures 1 and 3, 15 includes a recessed portion 167 adapted to receive cooperably a gear-like member 168 constructed of a suitable resilient material as rubber and adapted to fit into the recessed portion.

15 A coupling member 171, similarly recessed as coupling 166, is provided cooperatively adjacent to coupling 168 and the member 168 so that connection between the coupling members is readily made in such a manner that the exact alignment of the shafts carrying the coupling members is 20 not necessary.

20 The coupling member 171 is carried by shaft 172 of electric motor 173. This motor is carried upon a plate 174 positioned upon the top of the housing 11 and to which the motor is suitably affixed. The pump chamber 92 is also mounted upon this plate as by studs 176 so that the motor and pump are carried by the plate and are movable therewith.

25 The coupling 171 also carries a pulley 177 about which is extended the belt 178 which passes over another pulley 179 carried upon the shaft 122. The drive provided for the pump and for the rotating atomizing cup is therefore relatively simple, it being possible to adjust the tension 30 of the belt without disturbing alignment of the motor and pump.

35 In operation, the motor, the resistance unit or ignition element 33 and ballast resistor are connected to a suitable control unit 188 which may be conveniently in the form of a panel board having any suitable electrical timing control mechanism thereon. Thus, wires 181 are extended from the connectors 41 of the resistance unit and pass about the nozzle 63 and by the 40 nipple 56 between a cover member 182 and fan casing 61. These wires extend to the control unit as do other wires to the motor, these last mentioned wires not being shown. As I have indicated schematically in Figure 12 for the purposes 45 of illustration, the control unit is connected to a source of current supply, usually a 110 volt power line in which is connected any suitable master control switch 182^a. This control unit may have any suitable retarded relay 183 for automatically controlling closing of circuit 183^a to 50 electric motor 173; the coil 183^b of retarded relay 183 being connected in a circuit including wires 181, ignition or resistance element 33 and any suitable timing or warp switch 185. Such warp switch is normally closed when switch 182^a is open and the burner is not in operation; and it comprises bimetallic stem 185^a which is designed to warp a predetermined interval subsequent to closing of retarded relay 183, to break

55 the circuit through ignition element 33 by virtue of heating of the stem 185^a by means of shunt coil 185^b connected in motor circuit 183^a. Preferably retarded relay 183 is designed to close the motor circuit about 20 seconds after closing of 60 switch 182^a; and, as previously stated, warp 65 switch 185 is designed to open automatically subsequent to the closing of retarded relay 183 for energization of the motor. Thus when it is desired to effect operation of the burner, and start the burner into heat supplying operation, the 70 control upon closing of switch 182^a first supplies the current to the resistance element 33. I have found that this supply should include a period of about twenty seconds to heat up the element and block before the motor is started up. This 75 is accomplished by the timed closing of retarded relay 183, as was previously explained.

75 It is to be noted that the circuit shown includes the resistance element and a ballast resistor 184, so that the temperature of the resistance or ignition element, as previously explained, is practically constant. As a suitable ballast resistor, I have employed pure nickel wire, although other suitable materials having the correct temperature-resistance coefficient can be employed.

80 After the resistance element has been energized and the refractory block has become heated, the motor is energized by closing of retarded relay 183. It immediately turns over the 25 pump which as previously pointed out is connected for rotation with the motor by means of shaft 161; so that, very shortly thereafter, oil is supplied to the pressure chamber. Also, energization of the motor, effects rotation of fan 67 30 and atomizing cup 21 both mounted on tubular shaft 22 connected for rotation with the motor by means of belt 178. Supplying of oil to the pressure chamber builds up the oil pressure 35 therein and causes the piston 114 of the pressure responsive device 111 to be moved against the bias of the counterweight 141 so that the shutters 101 and 102 are moved relative to each other by means of the shutter actuating linkage including members 116, 127 and 132. However, due to 40 the bias placed upon the piston, the opening of the shutters does not take place immediately, and some oil is supplied to the rotating atomizing cup. This is facilitated by the fact that the orifice 24 is provided in the upper side of the 45 supply line 23 so that the oil cannot drain out of the line. Since the air is shut off, secondary atomization of the oil is not effected, and the oil is not discharged off of the atomizing cup in the path normally followed when the air is being supplied. The oil therefore strikes the refractory 50 block, is vaporized and ignited.

55 As the pressure builds up and the piston 114 is depressed in the cylinder, the shutters 102 and 101 are moved relative to each other so that the 60 air is supplied to the rotary atomizing cup, and secondary atomization of the oil is effected with the result that oil is no longer sprayed upon the refractory block but follows its normal path. The shutter control can also be readily made effective 65 when oil supply and control means other than a pump are used.

70 As I have previously explained, I have found that the air supply to the burner should be initially in very small quantities, since I have observed that a sudden rush of air is very apt to snuff out the flame. This is particularly so when starting into operation with a cold fire box which will not support or ignite the oil vapors. I therefore preferably provide the shutters in such a fashion that the apertures therein register successively instead of simultaneously so that, as the shutters are moved relative to each other, first one aperture opens and then another so that the quantity of air supplied is initially very small. 75

This is best illustrated in Figure 4 wherein it will be seen, by an examination of the position of the several apertures that as shutter 102 is advanced relative to shutter 101, aperture 186 first registers 5 with aperture 187, and upon further rotation, aperture 188 registers with aperture 189, and so on successively around the shutters for each set of the cooperative apertures. If all of the apertures registered simultaneously, and were opened 10 only to a very slight extent, the net area opened, when multiplied by the total number of apertures, would be quite considerable, and the quantity of air appreciable.

As soon as the burner starts into operation, and 15 the fire box begins to heat up, the control unit 180, by virtue of the automatic opening of switch 185 subsequent to closing of retarded relay 183 shuts off the current to the electrical resistance or ignition element 33, which thereupon is rapidly 20 cooled and is maintained at an atmospheric temperature by the circulation of air through the passage 48 and apertures 62.

In practice I have found that the burner construction just described is very positive, economical 25 to construct and efficient in operation.

In Figures 10, 11, 13 and 14, I have illustrated arrangements for supplying excess oil to the atomizing means so that, irrespective of the control effected over the air supply, the atomizing means 30 cannot deal adequately with the excess oil and the oil is discharged upon the refractory block with the result that the oil becomes ignited and the burner starts into operation.

In Figure 10 I have illustrated generally a device 35 200 which is adapted to be placed in the oil supply line 150, Figure 5, between the outlet from the pump and the inlet 81 to the pipe 23. The function of this device is to supply a flood of oil so positively that the atomizing cup, as it starts up 40 into operation, cannot atomize the oil adequately and the oil is discharged upon the refractory block. The device includes a cylinder 201 adapted to be placed in communication with the outlet for oil from the pump, or other oil control means 45 for the oil to the burner. The device includes a strainer 202 which is positioned in the cylinder so as to strain oil entering the same. A collapsible bellows 203 is positioned within the cylinder and is sealed at one end upon body member 204 50 with which the interior of the bellows is in communication. A by-pass 206 is provided about the bellows between the cylinder 201 and discharge connection 207. This by-pass includes a removable hollow plug 208. The plug has a passageway 55 209 therethrough and is adapted to be removed upon withdrawal of member 211.

In operation, upon oil being supplied to the cylinder, the bellows is caused to collapse as the oil pressure increases with the result that the excess oil contained in the bellows, the oil having 60 drained into the bellows after the burner's last operation, is forced out through the passage 207 and into the oil supply pipe 23. The normal supply of oil to the burner passes about the bellows through the by-pass 206.

In Figure 11 I have depicted another form of device for supplying an excess of oil. In this instance I preferably provide a cylinder 221 which is adapted to receive oil from the oil outlet of the pump. The oil is received through an inlet 222 which includes a strainer 223. The inlet is 70 in communication with a main cylinder chamber 224 in which a piston 225 is provided. Movement of this piston is regulated by a screw 226 so that the volume of oil discharged can be con-

trolled. The piston includes removable apertured screw plugs 227 which provide adjustable apertures so that the total quantity of oil passed through the burner can be regulated.

The passage of oil about the piston is controlled 5 by provision of the cooperating seating surfaces 230 formed upon cylinder head 228 and a resilient member 229 carried upon the piston so that oil passing through the burner, in normal operation, must pass through the apertured screw 10 plugs.

This structure likewise collects a quantity of oil above the piston when the burner is shut off, which quantity of oil is subsequently positively injected into the oil supply pipe immediately 15 upon the pump starting into operation and building up sufficient pressure to lift the piston against the contained oil.

The operation of these devices is much the same, in final effect, as the operation of the air 20 shutter control previously described. As is schematically depicted in Figure 13, a suitable control unit 180, similar in character to that disclosed schematically in Fig. 12, is provided for energizing the resistance unit 33 for a matter of 25 about twenty seconds prior to the time that the motor starts to drive the pump. Immediately upon the motor driving the pump, the excess oil means supplies the excess quantity of oil to the atomizing means with the result that the oil is 30 discharged upon and adjacent to the refractory block and its resistance element, to start the burner.

In Figure 14 I have schematically illustrated 35 the utilization of the excess oil supply means and the air supply control means. This particular combination has some advantages, particularly where it is desired that the burner start very positively into operation and that the oil be quite positively discharged upon the heated refractory block. In starting up in very cold climates, this sometimes proves desirable, a positive ignition being assured.

The operation of the system is much the same as that of the system previously described. The 45 control unit preliminarily energizes the resistance unit until the resistance unit and the refractory block become heated whereupon the motor starts the pump into operation. Immediately upon the pump, or oil supply means, going 50 into operation, the excess oil means supplies excess oil to the burner while the air shutter, or air supply control means, is thereafter energized to begin the supplying of air for effecting the secondary atomization. By this time the excess oil 55 supply, and the poor atomization effected by the oil atomizing means, in the absence of the secondary air, has resulted in the ignition of the oil upon the heated refractory.

The burner described, it is believed, possesses 60 numerous advantages and features over previous burner constructions; thus, it is relatively simple and inexpensive; the system of control is easily provided and does not include any expensive or complicated transformers or high tension apparatus; the burner unit is readily adapted to various installations. In this connection it is to be noted that I preferably provide the housing structure 71 upon a pedestal base including a pedestal 241 with respect to which the burner 70 is adjustably mounted by means of set screw 243 and a standard 242 engaging the housing 71. By this means, the burner can be readily moved up to a furnace door and the furnace does not have to be of a heavy construction as would have 75

to be to support the burner. The noise of operation of the burner is not transmitted into the furnace structure as in the present installations. This last feature, lack of noise transmission to the furnace, and through the furnace structure, is particularly desirable in domestic installations where relatively light furnace structures are employed. Further, the whole unit is self contained and is suitably enclosed, so that tampering and fooling with the burner structure is obviated in some measure. Thus, I preferably extend a housing cover 244 so that the oil unit is practically entirely enclosed.

I claim:

1. In an oil burner; an oil atomizing cup mounted for rotation, a fan casing, a fan mounted in the casing for rotation with the cup, an air discharge nozzle extending from the fan casing to discharge air about the cup, a secondary nozzle positioned about the discharge nozzle, an insulating block carried by the secondary nozzle adjacent to the atomizing cup and positioned out of the normal path of the atomized oil discharged from the cup, an electrical resistance element mounted on the insulating block out of the path of oil atomized off the cup, and means automatically controlled upon starting for causing oil atomized off the cup to contact the insulating block adjacent the resistance element to be ignited, the block having a passage therethrough to permit an air circulation over the resistance element to cool the same, the secondary nozzle including an aperture for admitting air to pass over the resistance element.
2. In an oil burner, an oil atomizing cup mounted for rotation, a fan casing, a fan mounted in the casing for rotation with the cup, an air discharge nozzle extending from the fan casing to discharge air from the fan about the cup, shutter means for controlling air admittance to the fan, a secondary nozzle positioned about the discharge nozzle, an insulating block carried by the secondary nozzle adjacent to the atomizing cup and positioned out of the normal path of the atomized oil discharged from the cup, an electrical resistance element mounted on the insulating block out of the path of oil atomized off the cup, and means automatically controlled upon starting for closing the shutter means to cause oil atomized off the cup to contact the insulating block adjacent the resistance element to be ignited, the shutter means including a pair of members relatively movable between a shut-off position and an open position in which air passes to the fan, each of the members including a plurality of apertures adapted to cooperate so that air admission to the fan following oil passage adjacent the heating element takes place relatively gradually, the block having a passage therethrough to permit an air circulation over the resistance element to cool the same, the secondary nozzle including an aperture for admitting air to pass over the resistance element.
3. In a fuel burner, oil ignition means, oil atomizing means positioned cooperatively with respect to the ignition means and adapted to discharge atomized oil normally out of contact with and beyond the ignition means, means for supplying a substantially predetermined quantity of oil under pressure to the atomizing means for normal atomization, and means responsive to the initial supplying of oil to the atomizing means for supplying a quantity of oil in excess of the predetermined quantity so that the atomizing

means discharges oil onto the ignition means during initial operation of the burner.

4. In a fuel burner, oil ignition means, oil atomizing means positioned cooperatively with respect to the ignition means and adapted to discharge atomized oil normally out of contact with and beyond the ignition means, means for supplying a substantially predetermined quantity of oil under pressure to the atomizing means for normal atomization, and means operable in response to the initiation of burner operation to supply a quantity of oil in excess of the predetermined quantity so that the atomizing means discharges oil onto the ignition means during initial operation of the burner.

5. In a fuel burner, oil ignition means, oil atomizing means positioned cooperatively with respect to the ignition means and adapted to discharge atomized oil normally out of contact with and beyond the ignition means, means for supplying a substantially predetermined quantity of oil under pressure to the atomizing means for normal atomization, and means responsive to the initial supplying of oil to the atomizing means for supplying a quantity of oil in excess of the predetermined quantity so that the atomizing means discharges oil onto the ignition means during initial operation of the burner, the excess oil supply means including a chamber containing a quantity of oil, and means actuated by initial supplying of oil to the atomizing means for discharging oil from the chamber so that an excess quantity of oil is supplied to the atomizing means.

6. In a fuel burner, oil ignition means, oil atomizing means positioned cooperatively with respect to the ignition means and adapted to discharge atomized oil normally out of contact with the ignition means, means for supplying oil under pressure to the atomizing means for atomization, means for conducting oil from the supply means to the atomizing means, means included in the conducting means for retaining a quantity of oil, and means for exhausting the retaining means to supply an excess quantity of oil to the atomizing means when the burner starts into operation so that oil is discharged onto the ignition means.

7. In a fuel burner, oil ignition means, oil atomizing means positioned cooperatively with respect to the ignition means and adapted to discharge atomized oil normally out of contact with the ignition means, means for supplying oil under pressure to the atomizing means for atomization, means for conducting oil from the supply means to the atomizing means, the conducting means including a chamber adapted to collect oil from the conducting means when the burner is not operating, a by-pass about the chamber for passing a predetermined quantity of oil to the atomizing means, and means responsive to the initial passage of oil through the conducting means to exhaust oil collected in the chamber onto the atomizing means as an excess quantity of oil.

8. A fuel burner comprising a tubular spraying cup rotatable about its axis, said cup having an annular fuel discharge lip from which fuel is sprayed in the form of a cone effected by rotation of said cup, a tubular nozzle member positioned about said cup and in spaced relationship with respect thereto, means for supplying a blast of air between said cup and said nozzle and directed against said cone to aid in spraying of fuel from said cup, an annular ignition element positioned about said nozzle, and means for controlling said blast of air to effect

alteration of said cone, whereby the fuel can be caused to selectively follow a path adjacent to or away from said ignition element.

9. In an oil burner, an oil spraying cup mounted for rotation, a fan casing, a fan mounted in said casing for rotation with said cup, an air discharge nozzle extending from said fan casing to discharge air about said cup, a tubular member positioned about said nozzle in spaced relationship with respect thereto, an insulating block in the space between said member and said nozzle adjacent said cup and positioned out of the normal path of oil sprayed from said cup, an electrical resistance element mounted on said insulating block, and means operable in response to the initiation of burner operation for causing oil sprayed off of said cup to follow a path different from said normal path to contact said block when it is desired to ignite said oil, said block having a passage therethrough to allow air circulation over the resistance element to cool the same, the structure formed by said member having an opening for admitting air into the space between said member and said nozzle for passage to said resistance element.

10. In an oil burner, an oil atomizing cup mounted for rotation, a fan casing, a fan mounted in said casing for rotation with said cup, an air discharge nozzle extending from said casing to discharge air about said cup, an insulating block about said air discharge nozzle and positioned out of the normal path of atomized oil discharged from said cup, an electrical ignition element mounted on said insulating block out of the path of oil atomized off of said cup, and means controlled upon starting for causing oil atomized off of said cup to contact the insulating block adjacent said ignition element to be ignited.

11. In an oil burner, an oil atomizing cup mounted for rotation, a fan casing, a fan mounted in said casing for rotation with said cup, an air discharge nozzle extending from said casing to discharge air about said cup, an insulating

block about said air discharge nozzle and positioned out of the normal path of atomized oil discharged from said cup, an electrical ignition element mounted on said insulating block out of the path of oil atomized off of said cup, and means controlled upon starting for causing oil atomized off of said cup to contact the insulating block adjacent said ignition element to be ignited, said block having a passage therethrough to permit air circulation over said ignition element to cool the same.

12. An oil burner comprising a motor actuated oil spraying and air feeding means including a fan having a casing with a discharge nozzle operable to direct a stream of air against the oil spray whereby the path of the sprayed oil may be varied in accordance with the magnitude of said stream of air discharged from said nozzle, an igniter positioned near said burner, means operable to initiate fuel feed for operation of said burner, and means operable in response to the initiation of burner operation for controlling said air stream to cause the oil to be initially sprayed in igniting relationship to said igniter and subsequently sprayed out of igniting relationship to said igniter.

13. A fuel burner comprising a tubular spraying member rotatable about an axis, said member having a fuel discharge lip from which fuel is sprayed, a tubular nozzle member positioned about said spraying member and in spaced relationship with respect thereto, means for supplying a stream of air between said spraying member and said nozzle and directed against the fuel spray to aid in spraying of fuel from said spraying member, an igniter positioned near said burner, and means for controlling said stream of air to effect alteration of said fuel spray, whereby fuel can be caused to selectively follow a path adjacent to or away from said igniter.

RENÉ M. VIDALIE.
